8. The p-type side of a germanium wafer 10 is soldered on to a boss 9 on the base of the copper can, as shown in FIGS. 5 and 6. Electrical contact is made to the n-type side of the wafer by means of a metal pad 11 carried on an insulating rod 12 on a spring 13 extending diametrically across the container 4 between supports 14 and 15. A connecting wire 16 extends between the pad 11 and a vacuum type electrical lead 17 (FIG. 3) extending through an insulating bush 18. When the specimen has been inserted the can is closed by the aluminium disc 5 and the can evacuated by means of a vacuum pump operating through the duct 8. The junction is now "drifted" by an ion drift process to give a p-i-n structure. When it is at an elevated temperature a reverse bias is applied to the junction and the depletion area slowly increases in thickness. At this time it is important to avoid thermal runaway. It will be appreciated that if the reverse current rises at a given temperature and reverse voltage (as it will do when the depletion area increases in thickness, the current being proportional to the thickness for large regions), extra power is dissipated. The temperature and thus the reverse current in the depletion area will rise still further and the system may become unstable and run away. In order to avoid this thermal run-away FIG. 7 shows a circuit for providing current limitation. In FIG. 7 the specimen indicated 19 is connected in series with a resistor R_2 and relay contacts RL' across + and - supply terminals of a D.C. supply which will normally be about 500 volts so that the D.C. voltage will be applied in reverse across the p-n junction. The voltage developed across R_2 is applied through a resistor R_1 to the grid of a valve V_1 which has a relay coil RL in its anode circuit and a capacitor C_1 connected between its anode and grid so that it acts as a Miller integrator. Initially the relay contacts RL' are closed and the reverse D.C. voltage across the p-n junction causes the junction to start to run away and hence the current increases. Increasing volts appear across the resistance R_2 applying a larger input voltage to the valve V_1 , the Miller has the property that

$$V_0 = \frac{-1}{R_1 C_1} \int V_i dt + \text{constant}$$

As the voltage across R_2 increases the anode cathode voltage of the valve drops and the relay coil takes more current until the contacts RL' open. The voltage across R_2 is now zero so that the current in the relay coil RL drops and the contacts again close. Thus the average current is held constant and the average power dissipated in the device held constant.

The time required to "drift" a given thickness is proportional to $(Pt)^{1/3}$ where P is the power dissipated in the device and t the time of "drift." The lifetime too of the material also affects the rate of "drift."

For typical material 500 v. and an average current of 2 ma. about 100 hours is required to "drift" 2 mm. A "drifted" region of 4 mm. or thereabouts would make a

reasonable spectrometer up to about 2 mev. gamma ray energy. This would require 800 hours "drift" at 1 watt or less time at higher powers.

After "drifting" the spectrometer is ready to use. The can and germanium are cooled to liquid air temperature by pouring liquid air into the Dewar vessel K, into which solid copper fins L dip. The reverse current of the junction drops now to less than 10^{-8} amps and noise from this current is negligible.

10 The device is connected in the circuit as shown in FIG. 8. Charge pulses in the p-i-n junction caused by the gamma rays are amplified by a low noise pulse amplifier and analysed by a pulse height analyser. Normal bias and load resistor values are about 50 volts and 50 meg-ohms respectively.

15 What we claim is:

1. A method of manufacturing solid state p-i-n junction devices consisting in the steps of first depositing onto a p-type semi-conductor a thin layer of lithium from a lithium vapor at about 700° C., depositing a protective coating thereon of aluminum to prevent oxidation, heating the semi-conductor to a temperature of about 200° C. to about 400° C. to cause the lithium to diffuse and to form a p-n junction and depletion zone and then applying a reverse electrical bias to the junction when heated to a lower temperature of approximately 70° C. to increase the thickness of the depletion zone and form a p-i-n junction.

2. A method of manufacturing solid state p-i-n junction devices consisting in depositing onto a p-type semi-conductor a thin layer of lithium from a lithium vapor at about 700° C. to form a p-n junction with a depletion zone, applying a protective coating on the lithium to prevent oxidation of the lithium, heating the semi-conductor to a lower temperature, and while so heated applying a reverse electrical bias to the junction to increase the thickness of the depletion zone and form a p-i-n junction.

3. The method of claim 2 wherein the semi-conductor is germanium.

40 4. The method of claim 2 wherein the protective covering is aluminum.
